UNITED STATES PATENT OFFICE.

JOHN EWING, OF SAN FRANCISCO, CALIFORNIA.

DESIGN FOR A HORSESHOE-PAD.

SPECIFICATION forming part of Design No. 34,378, dated April 16, 1901.

Application filed March 18, 1901. Serial No. 51,028. Term of patent 14 years.

To all whom it may concern:

Be it known that I, JOHN EWING, a citizen of the United States, residing in the city and county of San Francisco, State of California, have invented and produced a new and original Design for Horseshoe-Pads, of which the following is a specification, reference being had to the accompanying drawing, forming part thereof.

10 The figure is a perspective view of the pad. As shown in the drawing, the leading or material feature of my design consists of a segmental or crescent-shaped portion A, having a rear portion provided with ends extending approximately at right angles from the rear of the outer portion of the crescent portion, as shown at B. The crescent-shaped portion has its front end extended to form the thin flat plates or horns 2, and the lugs B 15 form a continuation of a solid block extending across the rear end and made integral and of

the same thickness with the crescent-shaped portion A. From the front portion of the projecting lugs B a beveled surface 3 connects the higher portions of the lugs with the 25 flat crescent-shaped portion 2 and gradually merges into said flat portion. From the central portion of the crescent A a convergent V-shaped projection 4 extends into the space between the horns.

Having thus described my invention, what I claim as new, and desire to secure by Letters Patent, is—

The design for a horseshoe-pad as herein shown and described. 35

In witness whereof I have hereunto set my hand.

JOHN EWING.
